INVENTOR:
ARTHUR P. YOUNG.
by *Edward William*
HIS ATTORNEY.

UNITED STATES PATENT OFFICE.

ARTHUR PRIMROSE YOUNG, OF KENILWORTH, ENGLAND.

MAGNETO-ELECTRIC MACHINE.

1,427,671.

Specification of Letters Patent. Patented Aug. 29, 1922.

Application filed November 15, 1920. Serial No. 424,062.

To all whom it may concern:

Be it known that I, ARTHUR PRIMROSE YOUNG, a citizen of Great Britain, residing at Dovedale, Kenilworth, in the county of 5 Warwickshire, England, have invented certain new and useful Improvements in Magneto-Electric Machines, of which the following is a specification.

This invention relates to magneto electric 10 machines such as are commonly used in combination with internal combustion engines to effect ignition within the cylinders and relates more particularly to devices which are known as impulse starters employed to 15 accelerate the armature of a magneto to produce a spark in one of the cylinders of the engine when the latter is being rotated at a low speed, for example when being turned by hand at starting.

20 In such a device the magneto is usually driven from the engine through a coupling, part of which forms the resilient connection between the driving and the driven member and is so arranged that the initial movement 25 of the engine shaft stresses this connection up to a certain point and after a predetermined movement the connection is free so that the magneto armature is again rotated or given an impulse so as to produce a spark 30 in the cylinder, the timing of the spark being arranged so that it occurs when the piston of the cylinder is in an appropriate position.

Impulse starters of this type usually consist of a member rigidly secured to the engine shaft and resiliently connected by 35 means of a spring to a member secured to the rotor shaft of the magneto this second member being provided with a catch adapted to engage with a fixed stop or projection so 40 that when the engine shaft is turned the magneto rotor is prevented from turning with it, and the motion of the engine shaft stores up energy in the resilient connection. Means are provided whereby the catch is 45 freed from the stop after the engine shaft has been rotated through a predetermined angle so that the energy stored up is utilized to give the rotor armature quick rotating motion or impulse sufficient to produce a 50 spark.

The present invention consists in an improved starter of this type.

In the accompanying drawings which

illustrate one form of my invention, Fig. 1 is an end elevation of a cover plate rigidly secured to the magneto casing. Fig. 2 is an end elevation of the member which is secured to the rotor shaft of the magneto. Fig. 3 is a similar view of the member which is secured to the engine shaft. Fig. 4 shows the members illustrated in Figs. 2 and 3 in their respective positions and Fig. 5 is a sectional elevation of the complete impulse starter assembled.

In carrying this invention into effect as 65 illustrated I provide a disc member 1 rigidly secured to the shaft of the magneto. This member is provided at its periphery with a longitudinal flange 2 having one or more radial apertures in which hardened 70 steel plungers 3 are adapted to slide. Surrounding this member is a second cup shaped member 4 which is resiliently secured to the disc member 1 by means of a strong spiral spring 5. The steel plungers 3 project 75 through the apertures in the flange 2 and are held in contact with the cup shaped surfaces formed on the inner side of the cup member by means of leaf springs 6. Mounted on pivots secured to the inner ends of 80 these plungers are biased pawls 7. These pawls are adapted to engage a stop or projection 8 formed on a cover plate 9 rigidly secured to the frame of the magneto. The cup shaped member 4 is rigidly secured to 85 the engine shaft and power is transmitted from the driving shaft to the magneto shaft through the spring 5 connecting the cup and disc members. The spring pressed plungers 3 are adapted normally to fit into two slight 90 recesses 9' formed at the ends of cam surfaces 10 formed on the inner side of the flange of the member 4 so that in addition to the spring 5 there is a certain mechanical connection between the cup and disc members 95 through these plungers. In operation, the engine or driving shaft is slowly rotated. The magneto shaft with the disc member attached to it will also rotate until one of the pawls 7 attached to the spring pressed 100 plungers comes in contact with the projection 8 secured to the magneto frame. No further movement of the magneto shaft can now take place and any further movement of the driving shaft causes the plunger 3 to 105 ride over the cam surfaces 10 on the inner

side of the cup member to force the spring 5 pressed plunger inward carrying with it the pawl which is attached to its inner end, and at the same time winding up the spring 5 forming the resilient connection between the coupling disc members. The profile of the cam 10 is so shaped that after a certain movement, the plungers will be forced inward to such an extent that the pawl is clear of the 10 projection 8 on the cover plate secured to the magneto frame, at which moment the disc member 1 and magneto shaft will be free to rotate which it does through a limited angle owing to the return of the spring 5 to its 15 normal position. The armature of the magneto thus receives a sharp impulse which is sufficient to produce a spark of strong intensity and is generally sufficient to start the engine. Assuming that it is sufficient to 20 start the engine the speed rapidly increases and the centrifugal action is sufficient to throw the heavy ends of the pawls 7 outwards thereby withdrawing the outer ends, so that they no longer come in contact with 25 the projection 8. Means would be provided to prevent the heavy ends of the pawls being thrown out too far from the centre in which case they might come in contact with the stops, as for example the pins 11 secured to 30 the pawls and engaging the inner side of the flange 2.

It will be obvious that in place of the flange 2 being circular it may be mutilated or cut away and only those portions left 35 through which the plungers 3 pass in which case the ends of the springs 6 would be held in place by means of pins secured to the disc member instead of entering slots formed in the flange 2 as illustrated.

40 What I claim as new and desire to secure by Letters Patent of the United States is:—

1. An impulse starter for an internal combustion engine in which the charge is ignited by a spark produced by a magneto electric machine comprising in combination a disc member rigidly secured to the shaft of the magneto, a cup shaped member surrounding the disc member and resiliently secured thereto, said cup shaped member being 45 also rigidly secured to the engine shaft, and a third member rigidly secured to the frame of the magneto, a pivoted pawl carried by the disc member, a stop on the third member engaged thereby and means for automatically withdrawing the pawl in a radial direction from engagement with the stop when the engine shaft has been rotated 50 through a predetermined angle.

2. An impulse starter for an internal combustion engine in which the charge is ignited by a spark produced by a magneto electric machine comprising in combination a disc member rigidly secured to the shaft of the magneto, a cup shaped member surrounding 60 the disc member and resiliently secured

thereto, said cup-shaped member being also rigidly secured to the engine shaft, and a third member rigidly secured to the frame of the magneto, a pivoted pawl carried by the disc member, a stop on the third member 70 engaged thereby a spring pressed plunger rigidly secured to said pawl and means for causing said plunger to move radially inward as the engine shaft is rotated.

3. An impulse starter for an internal combustion engine in which the charge is ignited by a spark produced by a magneto electric machine comprising in combination a disc member rigidly secured to the shaft of the magneto, a cup shaped member surrounding 80 the disc member and resiliently secured thereto, said cup shaped member being also rigidly secured to the engine shaft and a third member rigidly secured to the frame of the magneto, a pivoted pawl carried by 85 the disc member, a stop on the third member engaged thereby, a spring pressed plunger upon which the said pawl is pivoted, a cam surface formed on the cup shaped member adapted to engage said spring pressed 90 plunger and means for causing said cam surface to move the plunger inward so as to disengage the pawl from the stop.

4. In an impulse starter the combination of a spring pressed plunger mounted on a 95 rotatable member a pivoted pin carried by said plunger, a pawl mounted on said pin, a rigid stop adapted to be engaged by said pawl and means for moving the plunger against the action of the spring to release 100 the said pawl from said stop.

5. An impulse starter for an internal combustion engine in which the charge is ignited by a spark produced by a magneto electric machine comprising in combination a disc member rigidly secured to the shaft of the magneto, a cup shaped member surrounding the disc member rigidly secured to the engine shaft a spring connected at one end to the disc member and at the other end to the 105 cup shaped member, a third member rigidly secured to the frame of the magneto, a radially movable plunger carried by the disc member, a spring co-operating with said plunger, a pivoted pin rigidly secured to said plunger, a pawl mounted on said pivoted pin, a stop carried by the third member co-operating with the pawl and a cam formed 110 on the cup shaped member co-operating with the plunger.

6. An impulse starter for an internal combustion engine in which the charge is ignited by a spark produced by a magneto electric machine comprising in combination a disc member rigidly secured to the shaft of the 125 magneto, a cup shaped member surrounding the disc member rigidly secured to the engine shaft a spring connected at one end to the disc member and at the other end to the cup shaped member, a third member rigidly 130

secured to the frame of the magneto, two radially movable plungers carried by the disc member and arranged diametrically opposite each other, springs co-operating with 5 said plungers, pivoted pins rigidly secured to said plungers, pawls mounted on said pivoted pins, stops carried by the third member

co-operating with the pawls, and cams formed on the cup shaped member co-operating with the plungers.

In witness whereof, I have hereunto set my hand this 14th day of October 1920.

ARTHUR PRIMROSE YOUNG.
